UNITED STATES PATENT OFFICE

133,965

DESIGN FOR A NECKLACE

Massa Raimond, Malden, Mass.

Application September 1, 1942, Serial No. 108,095

Term of patent 3½ years

To all whom it may concern:

Be it known that I, Massa Raimond, a citizen of the United States of America, residing in Malden, county of Middlesex, and State of Massachusetts, have invented a new, original, and ornamental Design for a Necklace, of which the following is a specification, reference being had to the accompanying drawing, forming part thereof.

Fig. 1 is a plan view of a necklace showing my new design.

Fig. 2 is an edge view thereof.

I claim:

The ornamental design for a necklace, substantially as shown.

MASSA RAIMOND.
